(57) **CLAIM**

The ornamental design for a grow light for plants, as shown and described.

DESCRIPTION

FIG. 1 is a perspective view of a grow light for plants, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is an enlarged top plan elevational view thereof; and,
FIG. 7 is an enlarged bottom plan elevational view thereof.
The broken lines shown in the figure illustrate portions of the grow light for plants that form no part of the claimed design.
